(57) CLAIM

The ornamental design for a combination collapsible barbecue grill, table and bench, as shown and described.

DESCRIPTION

FIG. 1 is a perspective view of a combination collapsible barbecue grill, table and bench showing my new design, the broken lines being illustrative of a pole for supporting an umbrella and forming no part of my design;

FIG. 2 is a side elevational view thereof, the opposite side being mirror image;

FIG. 3 is a top plan view thereof;

FIG. 4 is a front elevational view thereof; and,

FIG. 5 is a rear elevational view thereof.
